COMBINED POULTRY FEEDER PIPE AND SUPPORT

Gerald L. Kitson, 9709 Belding Road,
Rockford, Mich. 49341

Continuation of design application Ser. No. 160,245, July
6, 1971, now Patent No. 229,030. This application Oct.
23, 1973, Ser. No. 408,372

Term of patent 14 years

Int. Cl. D8—08

U.S. Cl. D8—235

FIG. 1

FIG. 3

FIG. 4

FIG. 1 is a perspective view of a combined poultry feeder pipe and support embodying my new design shown within a feed trough, the latter being in dashed line to illustrate the environment.

FIG. 2 is a fragmentary top view of the combined poultry feeder pipe and support shown in FIG. 1.

FIG. 3 is a bottom view of the combined poultry feeder pipe and support shown in FIG. 1 and revealing the ported feeder pipe design.

FIG. 4 is a fragmentary side view of the combined poultry feeder pipe and support shown in FIGS. 1, 2, and 3.

In FIGS. 1 and 3 the bracketed portions are broken away and omitted to indicate indeterminate length of the footed poultry feeder pipe of my novel design.

This application is a continuation of my copending application Ser. No. 160,245, filed July 6, 1971, entitled Poultry Feeder Pipe Support, now Pat. No. D. 229,030.

I claim:

The ornamental design for a combined poultry feeder pipe and support, as shown and described.
